GAS LIGHTER

Charles F. Larsen, New York, N. Y.

Application August 28, 1935, Serial No. 38,270

2 Claims. (Cl. 67—6.1)

This invention relates to gas lighters, the function of which is to generate a spark to ignite a gas burner jet or other combustion equipment.

My invention is intended for use by mechanics and welders, such as for lighting welding torches, etc., and consequently has for one of its objects the provision of a device of this character of rugged substantial construction capable of withstanding the rough usage to which such devices are subjected.

A further object of my invention is to provide a gas lighter of simple and economic fabrication and of a compact arrangement so that same may be conveniently slipped into or removed from a pocket.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claims.

In the drawing:

Fig. 1 is a perspective view of my entire device.
30 Fig. 2 is a fragmentary side elevational view thereof; and

Fig. 3 is a longitudinal section taken on line 3—3 of Fig. 2.

Referring now to the drawing for a more detailed description thereof, the numeral 4 indicates a U-shaped flat spring member functioning as the handle and operating means of my device and comprising substantially parallel legs 5 and 6. The free end of the leg 5 is bent inwardly 40 at right angles to form a tongue 7 for the support of the flint holder 8, the tongue 7 having an aperture into which the holder 8 is installed.

The holder 8 comprises a tube 9, the bore of which is adapted to receive a flint or ferro-cerium rod 10 and having a collar 11 and a threaded portion 12 to receive a nut 13 by which the flint holder 8 is secured to the tongue 7. The bore of the tube 9 is threaded for a portion of its length adjacent its upper end to receive an adjustment screw 14, which screw engages a helical spring 15 pressing against the flint 10.

The leg 6 of the member 4 extends beyond the leg 5 and has its free end bent to form a box or frame 16. The side of the box 16 adjacent the tongue 7 is disposed at right angles to the leg 6 and is provided with an elongate slot 17 into which the tip of the flint holder 8 projects, thereby forming a guide for the latter.

Opposed ends of the box 16 are provided with

aligned holes to admit a spindle 18 having a threaded nut 19 and forming the support for an abrasive element 20. The element 20 is preferably cylindrical, the periphery of which is formed as a file to afford the necessary abrasion to the flint 10 as the latter is moved across the element 20 which, being cylindrical, may be readily turned on the spindle 18 to move an unused portion of its periphery 10. In use, the member 4 is gripped to move the legs 5 and 6 toward each other, during which the flint 10 is slid along the abrasive element 20, being guided by the slot 17, the abrasive action of the element 20 on the flint 10 thereby generating the required ignition spark.

It will be seen from the foregoing that my novel construction presents a compact practical arrangement, particularly the disposition of the flint holder between the legs 5 and 6 where the latter may be constructed of a length ample to contain a flint of greater length than was heretofore practical. It is also to be observed that the formation of the holding means for the abrasive element contiguous from one of the legs of the device provides a convenient means by which the active surface of the abrasive element may be readily removed as well as a substantial guide for the path of the flint to assure continued satisfactory service.

What is claimed as new is:

1. A lighter comprising a U-shaped resilient metallic member the legs of which are relatively movable toward and away from each other, a flint holder carried by one of said legs and disposed lengthwise of said member between the legs thereof and flint-striking means carried by the other leg, the latter being formed at its end to provide a substantially rectangular frame within which said flint-striking means is mounted and including a side transverse to said legs provided with an elongate slot in which a flint held by said holder may be guidedly moved in active cooperation with the flint-striking means.

2. A lighter comprising a substantially U-shaped resilient metallic member the legs of which are relatively movable toward and away from each other, one of said legs having its end bent at right angles to form a support for flint holding means, said flint holding means being disposed lengthwise of said member, flint striking means carried by the other leg, said other leg being formed at its end to provide an integral rectangular frame within which said flint striking means is mounted and including an arm contiguous on and transverse to said leg, said arm being provided with an elongate slot in which a flint held by said holder may be guidedly moved in active cooperation with the flint striking means.
